UNITED STATES PATENT OFFICE.

JOHN F. MURPHY, OF LOUISVILLE, KENTUCKY, ASSIGNOR TO JAMES M. ROBINSON, OF LOUISVILLE, KENTUCKY.

PORTABLE BATHROOM.

Application filed November 6, 1924. Serial No. 748,153.

This invention relates to a folding or portable bathroom of the type adapted to be transported as a unit and set up for use at convenient locations, and to also be folded or collapsed into a minimum space.

A primary object of the invention is to provide a unit of the character set forth including supporting means for the usual and necessary accessories, the said supporting means comprising a folding enclosure or screen which provides a rigid and practical structure both when closed and opened up for use, and also offers opportunity for contrasting ornamental decoration on opposite sides, thereby to provide an enclosure having the appearance of a bathroom from the inside and more appropriate decoration on the outside to effectively conceal the identity or character of the unit.

20 A further object of the invention is to provide a novel tub-supporting stand which forms a part of the support, the same being embodied in a form which materially assists in providing a well-balanced footing for the main supporting wall of the enclosure when the same is opened up for use.

With the above and other objects in view which will more readily appear as the nature of the invention is better understood 30 the same consists in the novel construction, combination and arrangement of parts hereinafter more fully described, illustrated and claimed.

A preferred and practical embodiment of 35 the invention is shown in the accompanying drawings:

Figure 1 is a perspective view of the unit set up for use.

Figure 2 is a perspective view similar to 40 Figure 1, but with the tub being folded into the out-of-use position and the screen or enclosure being shown in dotted lines.

Figure 3 is an enlarged detail view of the tub supporting bracket.

45 Figure 4 is an inside elevation of the bracket shown in Figure 3, the same showing one of the tub bearing elements in section.

Figure 5 is a detail top plan view of the 50 unit when in the out-of-use position.

Figure 6 is a detail elevation of one of the outside panels of the screen or support.

Similar reference characters designate

corresponding parts throughout the several figures of the drawings.

As previously indicated one of the principal objects of the present construction is to provide a novel portable room or enclosure offering the conveniences and facilities of a private bathroom. To that end it is proposed to provide a combined support and screen including a plurality of rigid framed sections hinged together whereby one of said sections constitute a main supporting wall 55 1 adapted to carry such fixtures or accessories as the cabinet C, heater H, fuel supply tank F and bracket designated generally as B, the latter serving as a support for one end of the tub and also adding stability to the frame of the unit when the wings there- 60 of are opened up for use.

The said main supporting wall 1 forms the back of the enclosure and has connected therewith the folding wall sections or wings 75 2, 3 and 4. The said wall 1 and wings are made by suitable framing members *a* connected by the hinges *b*, the said framing carrying wall-forming sheets C. Therefore, the main supporting wall 1 and the movable wings 2, 3 and 4 constitute a screen which may be opened up as shown in Figure 1 to cooperate with one of the walls of the room to provide a private bath enclosure, or when desired, can be folded as indicated by the dotted lines in Figure 2 and also as shown in Figure 5 thereby to form a complete enclosure for concealing the accessories previously referred to, as well as the tub T having a suitable drain pipe P.

80 The inside surface of the wall forming sheets *c* of the members 1, 2, 3 and 4 may be decorated to indicate a tile finish or the like, and also to provide a wainscoating effect as shown in Figures 1 and 2, while the outside thereof may be panelled, as indicated in Figure 6, and otherwise decorated.

85 The end frame of the wing 4 may be provided with hooks 5 for cooperating with hooks 6 on the upright exposed edge 7 of the frame of the main wall 1 thereby to hold the screen in its closed position as indicated by the dotted lines in Figure 2 and also in Figure 5.

90 The tub supporting and elevating bracket B preferably consists of the horizontal bars 100 8 and braces 9 which are connected to the in-

side surface of the wall 1 and the said bars 8 are connected at their front ends as indicated at 10 with the intermediate part of the fixed leg members 11. These leg members 11 are in turn connected by the cross tie 12 for the purpose of laterally bracing the same at a point below the bottom of the tub. This bracket being rigidly connected with the back wall 1 and extending forwardly therefrom serves to prevent the forward tilting of the wall 1 when the wings of the screen are opened out in substantially horizontal alignment. In other words this bracket assumes a part of the load carried by the inside face of the wall 1.

The said tub T is provided with a reinforced rear frame 13 which is formed with the offset bearing members 14 and also with the laterally projecting stop or abutment lugs 15 on each side of the tub. The said bearing members 14 terminate in a bearing foot or enlargement 16 adapted to have a rocking and sliding engagement on the inwardly offset lugs 17 carried by the intermediate portion of the leg 11. The said lug 17 may be provided with a cotter key 18 which is adapted to ride in the recessed portion 19 of the bearing foot 16 thereby to assist in guiding the tub in its movement from a horizontal into a vertical position. The upper ends of the legs 11 are provided with the seats 20 for receiving the projecting abutment lugs 15 of the rear tub frame when the tub is in its horizontal position thereby effectively providing for firmly supporting the tub when in its horizontal position. The front end of the tub is provided with the front supporting legs 22 as shown. It now will have been observed that the two points of support for the swinging end of the tub namely, 15-20 and 16-17 are disposed in offset relation in different vertical planes whereby the hinge support 16-17 is set closer to the main supporting wall 1 of the housing inclosure than the upper seat or rest 20 for the abutment 15. This is of practical importance because the result of locating the pivot point closer to the main supporting or back wall is that the tub, as it is raised or swung upwardly and backwardly, is moved closely to the main supporting or back wall so as to enclose the tank and put the equipment in the least possible space.

In view of the foregoing it will be apparent that the wall 1 and the bracket B cooperate to provide adequate support for the said wall 1 which carries the various accessories or apparatus convenient for use in a bathroom. Also when the folding wings 2, 3 and 4 are extended as shown in Figure 1 it will be apparent that the entire structure is effectively braced, while at the same time the screen folded out along one side of the tub gives adequate privacy and permits the making of a comfortable enclosure when

used in connection with one of the walls of a room. On the other hand the screen may be readily folded into the form shown in Figure 5 to completely inclose the tub and the accessories.

The bracket B is of particular importance in stabilizing the entire structure when the tub T is swung upwardly, but of course the folded walls 2, 3 and 4 also cooperate to provide adequate bracing against the unit accidentally turning over. Further by providing the rigid, rectangular hinged connected panels, there is provided a practical, as well as useful and ornamental screen which is far superior to ordinary curtains or their equivalent which not only fail to disguise the character of the unit but also do not permit of the desired range of ornamentation that is possible by using a sectional screen.

From the foregoing it will be apparent that the present invention provides a construction which is not unsightly when not in use, thereby avoiding the objection to devices or cabinets using merely a curtain or the like, and furthermore, owing to the novel way in which the bath tub is mounted, it is possible to make the device so that it occupies a minimum floor space. Furthermore, with the present device it may be pointed out that the novel sectional screen permits of practically enclosing the tub on three sides when in use, so that if the outfit is placed near one of the side walls or corner of a room it will give privacy to the bath nearly equal to that of a separate bath room.

In connection with the drain elbow of the drain pipe B it will be observed that the same is turned to one side, and the flexible hose constituting the pipe is arranged in such a way that the tub only twists the hose through an angle of about 90°, thereby avoiding undue twisting of the hose and making a very effective and long life connection.

Without further description it is thought that the features and advantages of the invention will be readily apparent to those skilled in the art, and it will of course be understood that changes in the form, proportion and minor details of construction may be resorted to without departing from the spirit of the invention and scope of the appended claims.

I claim:

1. A portable bathroom structure comprising a housing inclosure including a main supporting back wall adapted to carry bathroom fixtures, a bracket structure secured to said supporting back wall and extending forwardly thereof, and a folding bathtub having two points of support on said bracket structure respectively at different distances from the said supporting wall.

2. A portable bathroom structure comprising

- ing a housing inclosure including a main supporting back wall adapted to carry bathroom fixtures, a bracket structure secured to said supporting back wall and extending forwardly thereof, a folding bathtub having two points of support on said bracket structure respectively at different distances from the said supporting wall, the point of support nearer the supporting wall constituting the hinge or pivotal point for the tub.
3. A portable bathroom comprising a housing inclosure including a main supporting back wall adapted to carry bathroom fixtures, a stationary bracket structure secured to said wall and extending forwardly thereof, said bracket structure having bearing elements arranged respectively at different elevations and also respectively at different distances from the supporting wall, and the folding tub carrying at one end portion thereof separate pivot and abutment members which engage the bearing elements of the bracket structure respectively nearest and farthest from the supporting wall.
- 20 25 4. A bath structure comprising a tub frame having bearing seats and bearing studs spaced from each other and leg standards having bearing seats and bearing studs spaced from each other the seats of the legs adapted to receive the studs of the frame and the seats of the frame receiving the studs of the legs.
5. A bath structure comprising a tub frame having bearing seats and bearing studs spaced from each other and leg standards having bearing seats and bearing studs spaced from each other, the bearing surfaces of the seats of the frame and the legs being generally disposed in opposite directions, the seats of the legs adapted to receive the studs of the frame and the seats of the frame receiving the studs of the legs.
6. A bath structure comprising a tub frame having bearing seats and bearing studs spaced from each other, said seats and studs being offset with relation to each other, and leg standards having bearing seats and bearing studs spaced from each other, said seats and studs being offset with relation to each other, the seats of the legs adapted to receive the studs of the frame and the seats of the frame receiving the studs of the legs.

In testimony whereof I hereunto affix my signature.

JOHN F. MURPHY.
